UNITED STATES PATENT OFFICE

FREDERICK E. GREENE, OF HAMDEN, CONNECTICUT, ASSIGNOR TO THE ANDREW B. HENDRYX COMPANY, OF NEW HAVEN, CONNECTICUT, A CORPORATION OF CONNECTICUT

DESIGN FOR A BIRD-CAGE STAND

Application filed December 26, 1929. Serial No. 33,937. Term of patent 14 years.

To all whom it may concern:

Be it known that I, FREDERICK E. GREENE, a citizen of the United States, residing in the town of Hamden, county of New Haven, State of Connecticut, have invented a new, original, and ornamental Design for a Bird-Cage Stand, of which the following is a specification, reference being had to the accompanying drawing, forming part thereof.

The figure is a front elevational view of a bird cage stand, showing my new design.

I claim:

The ornamental design for a bird cage stand substantially as shown.

FREDERICK E. GREENE.
